UNITED STATES PATENT OFFICE

CONRAD D. YOUNGBERG, OF WOODSTOCK, ILLINOIS, ASSIGNOR TO WOODSTOCK TYPEWRITER COMPANY, OF WOODSTOCK, ILLINOIS, A CORPORATION OF ILLINOIS

TYPEWRITER

Application filed January 2, 1925. Serial No. 29.

This invention relates to the type bar action of typewriter mechanism, and has for its object the provision of means for actuating the type bars which shall be of improved construction and operation and in which the noise incident to their operation shall be reduced to a minimum.

The invention is exemplified in the combination and arrangement of parts shown in the accompanying drawing and described in the following specification, and it is more particularly pointed out in the appended claims.

In the drawing, the figure is a somewhat diagrammatic sectional view showing one embodiment of the present invention.

The invention is shown as applied to a power driven typewriter, such as that described and claimed in the patent of Otto A. Hokanson No. 1,614,475 granted January 18, 1927 for an improvement in power actuated typewriters, but it will be understood that the invention is applicable to other forms of typewriting machines.

The numeral 1 designates a typewriter frame having a motor actuated roller 2 journaled therein and driven by any suitable source of power. Key levers 3 are pivotally mounted at 4. The type bars 5 are pivoted at 6 on any well-known form of type bar support and are arranged to engage a platen 7. The type bars are actuated by sub-levers 8 pivoted at 9 on a cross-bar 10, the sub-levers being connected by pivots 11 to actuators 12. The actuators 12 are provided with teeth 13 in position to engage the teeth on the power rollers 2, the actuator being held out of engagement with the power roller by springs 14. The key levers 3 are provided with contact members 15 by means of which the actuators 12 are depressed to engage the rollers 2. This will produce movement of the sub-levers 8 and the type bars 5. The power for actuating the type bars is furnished from the power roller 2 and it is only necessary to exert sufficient force on the key levers 3 to move the actuator corresponding to the particular key lever depressed into engagement with the drive roller.

In front of the sub-levers 8 there is a bar

16 which extends across the typewriter frame and is provided with a plurality of plungers 17 slidably mounted in flanges 18 on the bar 16. One plunger 17 is provided for each sub-lever. The plungers 17 are provided with forwardly extending guide rods or screws 19 which are threaded into openings 20 in the plungers 17 and are provided with lock nuts 21 to hold them in adjusted positions relative to the plungers. Springs 22 are interposed between the lock nuts 21 and the front flange 18 to resiliently hold the plungers 17 rearwardly in the path of movement of the sub-levers 8.

When the key lever 3 is depressed to cause the power drive 2 to actuate the type bar, the sub-lever 8 will move from the full to the broken line position, as shown in the figure. This will actuate the plunger 17 to compress the spring 12 bringing the type bar to rest with just sufficient impact to make an impression upon the paper. The noise of the impact will thus be practically eliminated. The screw 19 and lock nut 21 may be adjusted to regulate the resistance of the spring 22 so as to produce the proper impact of the type. The stop member 17 being located adjacent the pivot of the spring will cause less noise upon contact with the sub-lever than would be the case if the parts were arrested at a point where the movement is greater. The location of the stop also makes it possible to enclose the parts in a sound retaining casing 23 which preferably comprises a layer 24 of fibrous material, such as felt, and a layer 25 of inert metal, such as lead. An outer supporting and stiffening plate 26 may be provided, which may be aluminum or any suitable material.

I claim:—

1. In a typewriter, the combination with a type bar, of actuating means therefor, comprising a pivoted sub-lever, a power roller, an actuator connected to said sub-lever, a key lever, means for connecting said actuator to said power roller to secure operation of said actuating means, and a spring-pressed plunger mounted in position to be engaged by said sub-lever when said type bar approaches its platen striking position.

100

2. In a typewriter, the combination with a type bar, of actuating means therefor comprising a pivoted sub-lever adapted to swing toward the keyboard when operated, a power roller, an actuator connected to said sub-lever, means for connecting said actuator to said power roller to secure operation of said actuating means, and a spring-pressed plunger spaced from said sub-lever when the latter is inactive but mounted in position to be engaged thereby above its pivot when said type bar is approaching platen striking position.
3. The combination with a typewriter comprising a type bar and power-operated actuating means therefor comprising a pivoted lever connected to the type bar, of a plunger individual to said lever, means for supporting said plunger for reciprocation forwardly and rearwardly but out of contact with said lever when the latter is inactive and in position to be engaged thereby when said type bar is approaching platen striking position, a cushioning spring acting on said plunger urging the same rearwardly toward said lever and adapted to be compressed when said plunger is moved forwardly by being engaged by said lever, and means for adjusting the position of said plunger relative to said lever to adjust the cushioning effect relative to the approach of the type bar to platen striking position.

In testimony whereof I have signed my name to this specification on this 30th day of December, A. D. 1924.

CONRAD D. YOUNGBERG.
